Primary Examiner — Abraham Bahta(74) *Attorney, Agent, or Firm* — Wood, Phillips, Katz, Clark & Mortimer(57) **CLAIM**

The ornamental design for a flexible pouch, as shown and described.

DESCRIPTION

FIG. 1 is a perspective view of a first embodiment of the flexible pouch showing my new design;

FIG. 2 is a front elevation view; the rear elevation view being a mirror image thereof;

FIG. 3 is a right side elevation view, the left side elevation view being a mirror image thereof;

FIG. 4 is a top view thereof;

FIG. 5 is a bottom view thereof;

FIG. 6 is a perspective view of the second embodiment of the flexible pouch;

FIG. 7 is a front elevation view thereof;

FIG. 8 is a rear elevation view thereof;

FIG. 9 is a right side elevation view thereof;

FIG. 10 is a left side view elevation thereof;

FIG. 11 is a top view thereof; and,

FIG. 12 is a bottom view thereof.

The broken line showing of portions of the claimed design is included for the purpose of illustrating environmental structure and forms no part of the claimed design.

1 Claim, 4 Drawing Sheets(56)
